Suspenders.

No 2237

Patented Sept. 4, 1841

UNITED STATES PATENT OFFICE.

DAVID B. COOK, OF NEW YORK, N. Y.

METHOD OF ATTACHING SUSPENDER-STRAPS TO PANTALOONS.

Specification of Letters Patent No. 2,237, dated September 4, 1841.

To all whom it may concern:

Be it known that I, DAVID B. COOK, of the city and State of New York, have invented a new and Improved Suspender-
5 Strap to be Attached to Pantaloons, thereby Causing the Pantaloons to Set Easy and Gracefully; and I do declare that the following is a full and exact description.

The nature of my invention consists in 10 attaching to the waist or waistband of the pantaloons a strap to be made of broad-cloth, india rubber, webbing, or any other material the pantaloons may be made of, (of the form and make as shown in the 15 drawings hereto annexed marked "A") of about eight inches in width, where it is attached to the pantaloons, two inches from the front of the waistband of the pantaloons to the back of the hip seams and gradually
20 tapering off to about one inch in width where it meets and is attached to the suspender buckle attached to the strap, being in length about six inches causing the pantaloons to set easy and gracefully and doing away
25 with the necessity of or for suspender buttons.

To enable others skilled in the art to make and use my invention, I will proceed to describe its construction, operation and application. I make a strap of the drawing herewith inclosed marked "A" made of the same material and color of the pantaloons. At the part of the drawings marked "B" the suspender buckle is attached to the strap. At the part marked "F," the 35 strap is attached to the pantaloons within about one inch of the front of the pantaloons. At the part marked "D and E" the strap is attached to the pantaloons along the waistband or top of the pantaloons. At the 40 part marked "F" it is attached to the pantaloons where it meets the hip seam to extend to the foot and extends about one inch back of the hip seam.

What I claim as my invention and desire 45 to secure by Letters Patent is—

Combining the suspender with the waist or waistband of the pantaloons by means of the strap attached to the pantaloons as herein set forth.

DAVID B. COOK.
